UNITED STATES PATENT OFFICE

130,767

DESIGN FOR A CAMERA

George A. Drucker, Chicago, Ill., assignor to Burke & James, Inc., Chicago, Ill., a corporation of Illinois

Application September 12, 1941, Serial No. 103,320

Term of patent 14 years

To all whom it may concern:

Be it known that I, George A. Drucker, a citizen of the United States, residing at Chicago, county of Cook, and State of Illinois, have invented a new, original, and ornamental Design for Cameras, of which the following is a specification, reference being had to the accompanying drawings forming a part thereof.

In the drawings, Figure 1 is a perspective view

from the front of the camera showing my new design, with the bellows extended.

Figure 2 is a view from the side of the camera opposite to that from which Figure 1 is taken, and showing the camera in a closed position.

I claim:

The ornamental design for a camera, as shown.

G. A. DRUCKER.
